UNITED STATES PATENT OFFICE.

ANTON LANG, OF DUSSELDORF, GERMANY.

SPARKING PLUG FOR INTERNAL-COMBUSTION ENGINES.

Application filed July 16, 1924, Serial No. 726,297, and in Germany May 24, 1924.

This invention relates to a sparking-plug for internal-combustion engines and of the kind provided with a hollow inner electrode adapted to be used for the introduction of starting-fuel or for circulating air or gases for cleaning purposes across the sparking-points.

The object of the invention is essentially to improve the plug with a view to obtain 10 a more reliable starting-action, and the invention consists in this respect in forming the sparking-points of the inner electrode on the edge of a dished plate adapted to retain introduced fuel and to maintain the 15 space above the sparking-points for some time charged with vapour, thereby ensuring almost certain ignition.

Means are also provided whereby the spacing of the sparking-elements may be 20 easily regulated and whereby the electric conductor can be applied to the sparking-plug in the most efficient manner.

Fig. 1 of the accompanying drawings represents a longitudinal section of the 25 sparking-plug, and

Fig. 2, an elevation of the sparking-elements.

The inner electrode *a* of the sparking plug has a central bore *b* which is carried 30 from the outer end of the electrode body almost to the inner end *h* of the same. Here the electrode body is reduced to receive a dished plate *f* on the up-turned edge of which the sparking-points *k* are formed. 35 A washer *g* is also applied to the reduced portion *h* which is upset to hold the washer and the plate *f* securely in position. Lateral slots *d* are made in the electrode just above the plate *f* so that fuel introduced 40 into the bore *b* for facilitating the starting of the engine, will be discharged into the plate and partly retained in its cavity *i*, the sparking-points *k* being left dry above the liquid. A shoulder *a*¹ on the electrode 45 body *a* supports, by means of a packing *r*, an insulating body *p* which is clamped in position by means of a nut *z* and another packing *s*, the nut *z* being screwed on a threaded portion *l* of the body *a* and formed 50 with recesses *4* for engagement with a suitable spanner. The insulating body *p* has a head to which a casing *o*, forming the outer electrode, is secured by means of a screw-threaded sleeve *q*, packings *r* and *s* being interposed between the abutting sur-

faces. The slotted portion of the body *a* and a distance *u* above this portion is spaced from the casing *o* so as to form a chamber *v* into which the liquid retained in the plate *f* can evaporate and form a fresh and easily ignitable mixture in the immediate neighborhood of the sparking-points. The sparking-points *y* of the outer electrode are formed on a ring *x* which is held in the lower end of the casing *o* either frictionally 60 or by a screw-thread so that it can be adjusted for regulating the distance between the points *y* and *k*. An inturned flange *w* at the orifice of the casing *o* prevents the ring *x* from being entirely withdrawn. The 65 sparking-points are separated by V-shaped notches. They are wide and chisel-shaped so that long edges *m* are formed along which the actual sparking-points *n* will be continually renewed by wear. The plate *f* 70 and the ring *x* are of equal diameter and formed with an equal number of points so that a ring of parallel spark brushes is produced around the cavity *i*. The ring and the plate act together as a condenser and 75 produce very powerful sparks. The sparking points are, owing to their position, effectively protected from splashes of oil and soot.

A sleeve *z*¹ is formed with an internal 80 screw-thread 8 whereby it is screwed on the outer portion 2 of the body *a*. This sleeve acts as a lock for the nut *z*, and between the two a ring 5 is arranged so as to be clamped in position. The ring 5 has a circumferential groove 6 in which another ring 95 9 is rotatively guided. The latter ring carries a radially arranged, screw-threaded stud 9 which is fitted with a nut 10 and serves as a terminal screw for the electric conductor. As this terminal can be turned about the plug into any suitable position, it is possible to connect up the conductor without bending and twisting the same. 100 The sleeve *z*¹ has also a screw-thread 12 for the reception of a valve plug 11 whereby the bore *b* is normally closed to the atmosphere. The plug 11 has a duct which opens into the sleeve *z*¹ above the valve seat so as to be out of communication with the bore *b* when the valve is closed and which can be used, when the valve is open, for introducing starting-fuel into the engine cylinder through the sparking-plug. The duct 105 of the plug 11 is widened out at 13 to form 110

a funnel. The valve plug is adjusted by means of a head 14 of insulating material.

I claim:—

1. A sparking plug of the character described comprising a hollow inner electrode, a dished plate connected to the lower end of said electrode, the edge of said plate being notched to form sparking points, the electrode being slotted immediately above the plate for feeding starting liquid into the latter, an outer electrode, and a ring of the same diameter as the dished plate depending from said outer electrode above the dished plate, said ring being notched 15 to form sparking points which coincide with those of the dished plate.

2. A sparking plug according to claim 1 in which the ring depending from the outer electrode is held in the latter so that it can be adjusted for regulating the distance 20 between the two sets of sparking points.

3. A sparking plug according to claim 1 in which the sparking points are chisel-shaped and the notches between them V-shaped.

4. In a sparking plug according to claim 1, a ring guided rotatably about the upper end of the inner electrode, and a terminal screw connected to said ring so that it can be turned by means of the latter to different angular positions about the plug.

ANTON LANG.
